ABSTRACT

A new and distinct cultivar of Chrysanthemum plant named White Reagan, bearing medium sized white blooms with a yellow-green center and a performance of 24-28 days.

2 Drawing Sheets**1**

This is a continuation of application Ser. No. 07/780,233 filed Oct. 22, 1991, now abandoned.

The present application is related to the following co-pending applications:

Application No.	Filing Date	Title
07/780,305	October 22, 1991	Reagan
07/780,237	October 22, 1991	Orange Reagan
08/088,104	July 8, 1993	Dark Reagan
08/101,275	August 2, 1993	Coral Reagan
08/092,942	July 19, 1993	Sulfur Reagan
08/092,943	July 19, 1993	Yellow Reagan
08/092,941	July 19, 1993	Bronze Reagan
08/101,278	August 2, 1993	Salmon Reagan

ORIGIN AND HISTORY OF THE NEW PLANT

The new plant of the present invention comprises a new and distinct cultivar of Chrysanthemum plant which is a naturally occurring sport of a Chrysanthemum named Reagan, which in turn is a cross of unknown *Chrysanthemum morifolium* parents. The Chrysanthemum named Reagan is described in copending U.S. patent application Ser. No. 07/780,305. The new cultivar was discovered in 1989 as a whole plant mutation by Martinus van der Jagt, in a greenhouse in Holland. The plant has been asexually reproduced by cuttings in greenhouses at Ter Aar, Holland. The new cultivar has been found to retain all of its distinctive characteristics through successive propagations.

2**SUMMARY OF THE NEW PLANT**

The present invention is a new and distinct variety of chrysanthemum of a medium sized bloom and white color.

BRIEF DESCRIPTION OF THE DRAWINGS

The present new and distinct Chrysanthemum cultivar is shown in the accompanying drawings, the color being as nearly true as possible with color photographs of this type.

Sheet 1 shows the full bloom of the new cultivar; Sheet 2, top, shows various stages of bloom of the new cultivar; and

Sheet 2, bottom, shows the foliage and petiole of the new cultivar.

DESCRIPTION OF THE INVENTION

This new variety of Chrysanthemum is of the botanical classification *Chrysanthemum morifolium*, and is named White Reagan. When grown in the vicinity of Ter Aar, Holland, it has a response time of approximately 7½ weeks. This new variety produces medium sized white blooms with a yellow green center having a 4 week performance (i.e., a vase life of 24-28 days). This new variety of Chrysanthemum has been found to retain its distinctive characteristics throughout successive propagations and may be planted under greenhouse conditions in Holland between weeks fifty and thirty-five (i.e., between December 1 and August 30). Pest

resistance, disease resistance and frost tolerance are unknown. The following is a description of the plant and characteristics (color designations are from the RHS Colour Chart) that distinguish it over related known varieties and its antecedents:

Botanical classification: *Chrysanthemum morifolium*.

Bud:

Size.—Medium (cross section) ± 1.0 cm, Height ± 0.7 cm.

Form.—Round and flat.

Outside color.—Yellow 4 D.

Bloom:

Size.—Medium.

Fully expanded.— $6\frac{1}{2}$ –7 cm.

Borne.—Upper portion, single flower per peduncle; Lower portion, plural flowers per peduncle.

Stems.—Strong, thick.

Form.—Single (Daisy).

Performance.—Very good 24–30 days (18°–20° C.).

Color:

Center of flower.—Immature: Yellow green 151 C; Mature: Yellow green 154 A.

Base of petals.—White 155 D but whiter and brighter.

Inside of petals.—White 155 D but whiter and brighter.

Reverse of petals.—White 155 D but whiter and brighter.

Outer petals.—White 155 D but whiter and brighter.

Tonality from a distance.—A white daisy with a fresh looking center having little or no pollen.

Discoloration.—None.

Pollen.—Yellow-orange 14 A.

Petals:

Texture.—Upperside smooth, underside smooth.

Number.—24–30 (two rows).

Cross-section.—Flat, two keels.

Arrangement.—Imbricated.

Persistence.—Good. Petals keep straight or reflex somewhat at the edge at the end of blooming.

Fragrance.—Typical Chrysanthemum.

Disc diameter.—1.5 cm.

Reproductive organs:

Stamen.—Yellow, thick, 3 mm in length.

Pollen.—Appears at a late stage of blooming, yellow-orange in color.

Styles.—Green thick. Length: ± 5 mm.

Stigmas.—Yellow. Width: ± 1 mm.

Ovaries.—Enclosed in calyx.

Plant:

Form.—Spray mum meant for erect culture. Herbaceous.

Growth.—Strong.

Height.—100–125 cm.

Peduncle.—Near the top ± 14 cm, near the middle ± 24 cm, near the bottom ± 28 cm.

Internodes.—3 cm.

Flowering response.—7½ weeks.

Foliation:

Color.—Upperside green 137 A, underside 137 C.

Size.—Length ± 12 cm, width ± 9 cm.

Quantity.—22–28.

Shape.—Lobed, see photograph.

Texture.—Upperside rough, underside smooth slightly hirsute.

Ribs and veins.—Ribs well developed, veins not so developed.

Edge.—Crenated.

5 Distinguishing characteristics of the Chrysanthemum of the Reagan family are summarized below in Tables IA and IB. Color designations therein are taken from the RHS Colour Chart.
